UNITED STATES PATENT OFFICE.

JAMES R. NUNAMAKER, OF HOOD RIVER, OREGON.

ADJUSTABLE GRADER.

1,109,866.

Specification of Letters Patent.

Patented Sept. 8, 1914.

Application filed December 24, 1913. Serial No. 808,625.

To all whom it may concern:

Be it known that I, JAMES R. NUNAMAKER, a citizen of the United States, and a resident of Hood River, in the county of 5 Hood River, State of Oregon, have invented a new and useful Improvement in Adjustable Graders, of which the following is a specification.

This invention relates to machines for 10 mechanically segregating apples, or other objects of approximately round shape, into groups of graded sizes.

The purpose of my invention is to accomplish the grading in an efficient manner, 15 and by simple means.

To this end my grader consists of a rack comprising a plurality of parallel bars spaced apart, and means whereby the spaces between said bars may be varied and ad- 20 justed as desired to effect any particular grading. The graded material, falling through the bars, drops into a chute for delivery to the boxes to be packed.

The details of my invention are herein- 25 after fully set forth.

In the accompanying drawings: Figure 1 is a front elevation of my machine; the delivery chute being shown in broken lines for the purpose of showing certain other 30 parts with greater clearness; Fig. 2 is a vertical, longitudinal cross-section taken on the line 2-2 of Fig. 1; Fig. 3 is a partial plan view of the far side of the machine; and Fig. 4 is a detail of construction.

The body of my machine is of rectangular 35 box-shape having fixed sides, *a*, *a*, a fixed back end, *b*, and a movable front end *c*. The bottom of this box consists of a plurality of movable rack-bars *d*. The body 40 is mounted on legs, *e*, which are preferably rigidly braced by the bars *f*, *f'*. A chute *g*, made of some soft, flexible material, is supported beneath the box bottom of the body so as to catch the graded material falling 45 through between the rack bars and conduct it to suitable packing boxes, the latter not being shown in the drawings.

The sides, *a*, *a*, are made with longitudinal slots *h* at the base, and the bottom of such 50 slots are covered by strips, *i*, of some good wearing material, as iron. Flat bars of iron *j* are slidably seated in the slots, *h*, the ends of these bars being twisted to a vertical plane, as at *k* in Figs. 1 and 3. The bars, *d*, are made half round in cross section, and 55 are fastened at their flat faces on the iron

bars *j*. The front end, *c*, of the body is fastened on the foremost rack bar *d'*. To insure against the fruit or other articles being crushed, the rack bars, *d*, the sides, *a*, *a*, 60 and the ends of the box body are padded as indicated by *m*, *n*, and *o*, *o'* respectively.

Bolted by bolts *l* on the supports, *p*, *p'*, to sides of the box-body are parallel notched arc bars *q*. A strut *p'* acts as a 65 brace for the supports *p'*. A shaft *r*, in alinement with the centers of the arc bars, *q*, is rotatably journaled in the rear legs, *e*, and an intermediate bearing *s*. See Figs. 1 and 2. Levers, *t*, are rigid on the ends of 70 the shaft *r* and are provided with spring pawls, *u*, adapted to be engaged with the notches of the arc bars *q*, so as to lock the levers in position as adjusted. On the levers, *t*, are a plurality of collars *v*, spaced 75 equi-distant apart and secured in place by set-screws. The collars are made with eyes *v'*, and the ends, *k*, of the flat bars *j* (see Fig. 4) are perforated and hold an eye-bolt *w* locked in place by the nuts *x*; 80 and rods *y* connect the eye bolt *w* with the collars *v* in such manner that by operating the levers *t* the bars *j* may be correspondingly brought closer together or moved farther apart, according to the degree of 85 movement of said levers, for the purpose of varying the grading spaces between said bars *j*. By having the arc bars *q* graduated to a predetermined scale, the proper movement of the rack bars *j* may be facilitated relatively to the grading to be done. 90

I claim:

1. An adjustable grader comprising a body having sides and ends, a plurality of grading bars movably supported between 95 the sides, one of the ends of the body being carried by one of said bars, a lever element and connections therefrom to said bars adapted for moving the latter simultaneously toward and from each other, and whereby said bars are positioned equidistantly from each other.

2. An adjustable grader comprising a body having sides and ends, a plurality of grading bars movably supported between the 105 sides, one of the ends of the body being carried by one of said bars, a lever element and connections therefrom to said bars adapted for moving the latter simultaneously toward and from each other, and whereby said bars are positioned equidistantly from each other, means for gaging the movement of the lever 110

element relatively to the desired spacing of the bars, and means for locking the lever element in place as adjusted.

3. An adjustable grader comprising a body having sides and ends, a plurality of grading bars movably supported between the sides, one of the ends of the body being carried by one of said bars, levers fulcrumed at the sides of the body, rods connecting said levers with the bars respectively, means for gaging the movement of the levers relatively to the desired spacing of the bars, and means for locking the levers in place as adjusted.

4. An adjustable grader comprising a body having sides and ends, a plurality of grading bars movably supported between the sides, one of the ends of the body being carried by one of said bars, levers fulcrumed at the sides of the body, collars adjustably mounted on said levers, rods connecting said

collars with the bars respectively, means for gaging the movement of the levers relatively to the desired spacing of the bars, and means for locking the levers in place as adjusted. 25

5. An adjustable grader comprising a body having sides and ends, the sides being provided with horizontal slots at the bottom, a plurality of grading bars bearing at their ends in said slots of the sides, one of the ends 30 of the body being carried by one of said bars, levers fulcrumed at the sides of the body, collars adjustably mounted on said levers, rods connecting said collars with the ends of said bars respectively, notched arc bars, and 35 spring-controlled pawls on the levers engaging therewith.

JAMES R. NUNAMAKER.
